SWITCH

Filed Feb. 12, 1925

Fig. 3.

UNITED STATES PATENT OFFICE.

LEE J. VOORHEES, OF NEW YORK, N. Y., ASSIGNOR TO NATIONAL CARBON COMPANY, INC., A CORPORATION OF NEW YORK.

SWITCH.

Application filed February 12, 1925. Serial No. 8,803.

This invention relates to circuit closing means for battery hand lamps and the like. Some of the features, at least, are useful in switches for other purposes, however.

- 5 The principal object of the invention is to provide a battery hand lamp switch which is simple in construction and operation and reliable in use, and which can be manufactured at low cost.
- 10 It is a further object to provide a switch which can be mounted upon either a flat or round casing, or even at the edge or corner of a casing and which will not be confined against operation by the space restriction
- 15 within the casing adjacent such round surface, edge or corner. Such a switch may be advantageously adopted as standard where many different types of battery hand lamps are manufactured.
- 20 In the drawings, Fig. 1 is an elevation of a battery hand lamp embodying the improvements of the present invention;
- Fig. 2 is an elevation of the switch mechanism as seen from the inside of the casing;
- 25 Fig. 3 is a horizontal section showing the switch lever in open position, the closed position being indicated in dotted lines; and
- Fig. 4 is a vertical section showing the switch lever and the means whereby it is supported and guided.
- 30 The battery hand lamp may comprise a body casing 1, a head 2 including the usual reflector and lens, an electric lamp 3, and a battery comprising cells 4 electrically connected in series. One of the lamp terminals is always electrically connected to the battery and the other is electrically connected through the casing 1 or other suitable conducting means to a tumbler switch designated generally by the numeral 5 and illustrated in detail in Figs. 2, 3 and 4. The switch 5 consists essentially of two elements, a lever 9 which is a conducting element swingable into and out of engagement with a contact 6 that is connected with battery terminal 7, to make and break the circuit to the lamp 3, and a member 10 which serves as a bearing and guide for the lever 9 and also forms a spring to control the movements of the lever.
- 35 The lever 9 comprises a handle 11 that extends through a small opening 12 in a wall of the casing 1, a ball or enlargement 13 seated in said opening at the inner side of said wall, and an inwardly projecting end 14 movable
- 40 into and out of contact with the battery ter-

50 minal 7. The construction of the bearing portion as a ball is economical because the ball can be made at one operation with the forming of the handle 11 and the inwardly projecting lever end 14.

55 The member 10, which is stamped and formed from a piece of conducting sheet metal, comprises a base 15 that is secured to the casing 1 by rivets 16 and that has an opening (not shown) through which the ball 13 can be passed. Upturned sides 17 on the base 15 are curved inward and cooperate with the interior of the casing 1 to form a socket bearing for the ball 13. The edges 18 of the curved side members 17 are straight and parallel and just far enough apart to permit easy passage of the inwardly projecting end portion 14 of the lever 9. The edges 18 guide the lever 9, confining it to movement in a single plane at right angles to the base 15 and the side of the casing 1 on which the base is mounted. The member 10 also includes means for pressing the end 14 of the lever 9 into firm contact with the battery terminal 7 and for holding it stationary at its opposite limit of movement when idle. An upstanding end wall 19 on the base 15 has long spring fingers 20 formed to converge gradually into contact or nearly into contact with each other and then to diverge gradually at their ends, 60 whereby a narrow neck is formed through which the lever end must pass in moving between circuit closing and open positions. The fingers 20 squeeze the end 14 of the lever 9 urging it with a snap action to either limit of 65 its movement toward which it is moved by the handle 11 from the central position. In the circuit closing position of the lever 9 the fingers 20 press the lever against the battery terminal 7 firmly enough to make a good conductive contact therewith. The lever end 14 is squeezed by the fingers 20 which may transmit the current from the lever end to the casing. The force exerted by the fingers upon the lever also presses the ball 13 into firm contact with the casing 1 so that good conduction 70 may be obtained through this means also.

75 When the switch lever 9 is moved away from the circuit closing position to the opposite side of the central position, the fingers 20 urge it on in this direction until the lever handle 11 engages the edge of the opening 12 in the casing wall. The fingers 20 hold the lever stationary in this position, thus preventing the lever from making accidental 80

contact with the battery terminal 7 and also keeping it from shaking and rattling about.

The lever pivot is so near the casing 1 that only a small opening in the casing is required to permit the lever to operate. This opening 12 is completely closed at all times by the ball so that it is hardly noticeable and can never admit harmful substances to the interior of the casing.

14 In assembling the above described parts the lever end 14 and the ball 13 may first be passed through the hole in the base 15, and the lever handle 11 inserted through the hole 12 in the casing 1, after which the rivets 16 may be applied to secure the member 10 and the lever 9 operatively to the casing.

The tubular switch 5, consisting as it does of only two simple, inexpensive, and easily assembled pieces, may be manufactured at 20 low cost, both as to labor and material. The switch is reliable in use because there is little liability of disarrangement or breakage.

The switch mechanism described is of universal application. It can be applied with 25 equal facility on a flat or rounded surface of a casing or at the edge or corner thereof, by altering the shape of the base slightly to meet the particular requirements. Since the switch lever is pivoted almost at the casing 30 and swings transversely thereof it would not be handicapped in its operation by the space restriction imposed within a casing corner.

Variations may be resorted to within the scope of the invention and parts of the improvements may be used without others.

I claim:

1. In a switch, the combination of a conductive supports; a conductive switch lever having a handle at one side of said support and both an enlarged portion and a contact-making portion at the other side of said support; means providing a bearing for said enlarged portion, and a conductor engageable by said contact-making portion, whereby said lever serves to electrically connect said conductor and said support.

2. In a switch, the combination with a support; of a switch lever having a handle, an enlargement, and a contact-making portion; and a unitary member comprising a bearing for said enlargement, guiding means for said lever, and means for throwing said lever into open or closed position.

3. A switch as defined in claim 2, in which 55 said unitary member is formed from sheet metal and said means for throwing the lever comprises resilient sheet metal finger means integral with said member.

4. In a battery operated device, the combination of a casing having an opening in a wall thereof; a switch lever extending through said opening comprising a handle outside said casing, and both an enlargement and a contact-making portion inside said casing; a conductor inside said casing; and a

unitary sheet metal member secured inside of said casing and comprising a bearing for said enlargement, guiding means for said lever, and resilient means for throwing the contact-making portion of said lever against 70 and away from said conductor.

5. In a battery hand lamp, the combination with a casing having an opening therein, of a two part switch, the first part being a switch lever extending through said opening and swingable to open and close the electric circuit of the lamp, and the second part comprising a base secured to the casing, side members formed on the base to form a socket bearing and guides for the lever, and spring 80 means extending across the base constructed and arranged to press the lever to either limit of its movement.

6. In a battery hand lamp, the combination with a casing, of a switch lever pivoted 85 to swing between circuit making and open positions, and an integral guide and detent member for controlling the lever comprising a base secured to the casing, guides on said base, and spring means extending from said 90 member and engaging the lever so guided, the spring means being arranged to yield when the lever is moved from closed or open position, and then to snap it to the position toward which it is moved.

95 7. In a battery hand lamp, the combination with a casing, of a contact making member movable between open and closed positions and combined guide and detent means within the casing for controlling said member comprising guides beyond which a portion of the member projects, and spring fingers above the guides at opposite sides of the path defined by them, arranged to form a narrow neck through which the projecting 105 portion of the contact making member passes in moving between open and closed positions, and to diverge gradually in both directions from said neck, so that the contact making member when moved beyond the 110 neck in either direction is urged to the limit of its movement in that direction by the fingers and is detained there by them.

8. In a switch, in combination, a one-piece 115 lever comprising a handle, a bearing portion and a conductive contact making end all symmetrically formed with reference to the longitudinal axis of the lever so that the lever can be completely formed at one turning operation, and means to support and guide the conductive end of said lever between circuit closing and open positions.

9. In an electric switch, the combination with contacting means, of supporting means therefor comprising a base of sheet metal having a bearing surface adapted to be engaged by said contacting means and having resilient integral fingers substantially parallel to said base and arranged on opposite sides 125 of the path of movement of said contacting 130

means to cooperate with the latter during such movement.

10. In an electric switch, the combination with an oscillating lever, of supporting means therefor comprising a base having a bearing and guide means for said lever, said base also having integral means operative to snap said lever into its open and closed positions.

11. In an electric switch, the combination ¹⁰ with an oscillating lever having a handle at one end, contacting means adjacent its other end and an enlargement between said ends; of supporting means for said lever comprising a base having means providing a bearing for ¹⁵ said enlargement, said means comprising upwardly and inwardly extending tongues, the

opposed edges of said tongues forming a passage through which said lever projects and whereby the latter is guided when oscillated.

12. In an electric switch, the combination ²⁰ with an oscillating switch lever having a handle at one end, contacting means adjacent its other end, and an enlargement between said ends; of supporting means for said lever comprising a base having a socket forming a ²⁵ bearing for said enlargement, a passage whereby said lever is guided, and integral finger means cooperating with said lever to snap it into its open and closed circuit positions.

In testimony whereof, I affix my signature.
LEE J. VOORHEES.
